(Cl. D30—1)

FIG. 1 is a top plan view of a firearm showing our new design.

FIG. 2 is a side view of the firearm.

FIG. 3 is a bottom view of the firearm.

The undisclosed side of the firearm is substantially the same in appearance as the side shown.

The essential features of the firearm reside in the portions shown in full lines.

The end of the gun stock is plain in appearance as indicated in the several figures.

We claim:

The ornamental design for a firearm as shown and described.
